UNITED STATES PATENT OFFICE

170,386

COMBINATION METAL AND PLASTIC SPECTACLE FRONT

John J. Rohrbach, Rochester, N. Y., assignor to
Shuron Optical Company, Inc., Geneva, N. Y.,
a corporation of New York

Application February 16, 1952, Serial No. 18,547

Term of patent 14 years

(Cl. D57—1)

To all whom it may concern:

Be it known that I, John J. Rohrbach, a citizen of the United States of America and resident of Rochester, in the county of Monroe and State of New York, have invented a new, original, and ornamental Design for a Combination Metal and Plastic Spectacle Front, of which the following is a specification, reference being had to the accompanying drawing forming a part thereof.

In the drawing:

Figure 1 is a front elevational view of a combination metal and plastic spectacle front, showing my new design;

Figure 2 is a top plan view thereof; and

Figure 3 is an end elevational view.

The essential features of my design reside in

the parts shown in full lines. The dotted lines in Figures 2 and 3 indicating a fragmentary showing of temples are for illustrative purposes only.

I claim:

The ornamental design for a combination metal and plastic spectacle front, substantially as shown and described.

JOHN J. ROHRBACH.
